UNITED STATES PATENT OFFICE.

WILLIAM C. HORNER, OF INDIANAPOLIS, INDIANA, ASSIGNOR TO
CHARLES P. McDougall, OF INDIANAPOLIS, INDIANA.

DESIGN FOR A KITCHEN-CABINET TOP.

No. 37,897.

Specification for Design.

Patented March 13, 1906.

Application filed October 7, 1905. Serial No. 281,860. Term of patent 14 years.

To all whom it may concern:

Be it known that I, WILLIAM C. HORNER, a citizen of the United States, residing at Indianapolis, in the county of Marion and State of Indiana, have invented a certain new, original, and ornamental Design for Kitchen-Cabinets, of which the following is a specification.

The figure of the drawing illustrates a per-

spective view of a kitchen-cabinet embodying my design.

I claim—

The ornamental design for a kitchen-cabinet top as shown.

WILLIAM C. HORNER. [L. S.]
